WATER FAUCET

Otto Schopp, Phoenix, Ariz.

Application October 27, 1947, Serial No. 782,373

3 Claims. (Cl. 137—710)

1

This invention relates to water faucets and has for its objects:

First, the provision of a faucet which can be easily and cheaply made and is particularly adapted to operation on a wall or partition where space is limited;

Second, the provision of a faucet having an attachment plate to adapt it to mounting on a vertical wall or partition with the spout and handle arranged to swing toward the wall when not in use so that a minimum of extending or protruding parts are necessary;

Third, the provision of a faucet having a tubular body with an attachment flange parallel with its axis and an inlet opening formed on the outer face of said flange and a valve stem operating axially in said body and at one end thereof, a curved swinging spout axially operative in the opposite end of said body and a restricted passageway leading from said valve through said body to said spout;

Fourth, a compact faucet for side wall mounting having an outward swinging spout and its parts and passageways arranged so that it is dripless after being shut off; and

Fifth, a water faucet having a cylindrical body with a mounting flange formed tangent to its periphery having an inlet; one end of the body being provided with an axial chamber with a valve seat at its bottom connecting with said inlet, and a valve having a stem bushed therein and threaded to close axially on said seat, the opposite end having an axial chamber bushed to enclose a rotatable spout, and a plurality of parts forming a constricted area leading from said valve seat chamber through said body to said spout chamber.

Other objects will appear hereinafter.

I attain the foregoing objects by means of the device and its component parts illustrated in the accompanying drawings in which—

Figure 1 is an elevational view of the valve as applied to a vertical wall surface;

Figure 2, side elevation thereof;

Figure 3, a plan view of a horizontal section taken substantially on line 3—3, Figure 1, and drawn on a somewhat enlarged scale, with the valve in closed position;

Figure 4, a plan view of a similar horizontal section with the valve open;

Figure 5, a section taken transversely through the valve body substantially on line 5—5, Figure 4;

Figure 6, a section taken transversely through the valve body on line 6—6, Figure 4;

Figure 7, a section taken transversely through the valve body on line 7—7, Figure 4;

2

Figure 8, a plan view of the back of the attaching flange; and

Figure 9, an elevation of a slightly modified form of valve body adapted for vertical installation.

Similar numerals indicate similar parts in the several views.

The body 2 of the valve is cast of metal shaped to provide a cylindrical portion 3 to which an attaching flange 4 is joined tangentially along its periphery. One end of the cylindrical portion is bored axially to form a valve chamber 5, and the opposite end is bored to form a swing spout chamber 6.

A valve seat 7 is formed at the bottom of the valve chamber and the axial opening in this seat opens into a bore 8 leading to an inlet 9 on the back face of flange 4. Outward from this seat the bore of chamber 6 is tapped to provide a steep pitch square thread 11 which accepts the closing screw 10 on valve stem 12. A packing nut 14 is then threaded into the end of the body to enclose the stem and compress packing ring 16. On the end of stem 12 a single wing handle 17 is splined and held by a set screw. A closing spring 18 surrounds shaft 12 with one end anchored to flange 4 and the other set into handle 17.

The inner portion of spout chamber 6 is drilled and threaded to receive the axial portion 24 of spout 19, and the outer portion threaded to receive gland nut 20. A portion of the wall of chamber 6 is broken away to communicate with each of three port holes 22, drilled through the body part 3 parallel with its axis but eccentrically positioned therefrom and opening into the valve chamber 5. The combined cross sectional area of these three holes is less than that of either the inlet 9 or spout 19, and together they form a constricted transfer passageway from the valve chamber 5 to the spout chamber 6.

The spout has a threaded axial portion 24 which retains it in position, and is then bent at right angles to provide a delivery bib extending from portion 25 at an angle of 90° relative to the axial portion 24. This construction enables the spout to be swung out outward for delivery as shown by the solid lines in Fig. 2, or rotated to an out-of-the-way position as indicated by the dotted outline 26.

The valve form shown in Figure 9 is of similar construction except that the outer tip 35 of spout 19 is bent downward to be parallel to the inner threaded portion 24.

The advantages of construction are obvious. By providing a valve body with a cylindrical body 3 tangentially joined to an attaching flange 4,

with all valve parts and passageways are contained within the body and with a spout which may be folded close to the plane of the base of the attaching flange and a swing out handle 17, the valve is very compact and is advantageous where space is to be conserved.

In use, the flange 4 is attached to a wall 27, which may be a sink back, or other vertical member, and the inlet tube 39 attached to a water supply pipe. The valve thread 11, having a steep pitch, will open the valve on a quarter or half turn. The handle is, therefore, positioned on the stem so that it is vertical when the valve plug 13 is seated, as shown in Figure 3. When not in use, the spout 19 is kept in the raised position, as shown in Figure 2, or swung to one side as indicated by numeral 38, Figure 9. When it is to be used it is turned to the outward extended position. Outward motion of the handle 17 then opens the valve against the tension of spring 18. A return motion closes it and this is accelerated by the urge of this spring.

When the valve is opened water flows from the inlet into the valve seat chamber 5, as indicated by the arrows Figure 4. It then reverses its direction and flows through holes 22 at an increased velocity due to the constricted area of these holes, and thence at a slower velocity, into and through chamber 6 and, lastly, out through spout 19. Now, when valve plug 28 is closed on seat 7 to effect a shut off, water flowing through holes 22 at the greater velocity will continue to flow on through chamber 6 and out of spout 19 for an instant due to its momentum of flow. This breaks the water columns flowing through these holes forming a partial vacuum in each. An instant after the vacuum has formed the out flow of water from the spout tip is stopped and the end portion of water in the spout drawn back into the spout by atmospheric pressure. The quicker the closing action the greater is the vacuum action. Spring 18 assists in this. This action prevents any drip from the spout since the water is drawn back into it and away from its mouth. The size and shape of the spout is such that the water in it does not tend to run out after the closing of the valve, and after it has been drawn away from the tip of the spout. Thus, since there is no water left at the tip of the spout to drip off, and since the remaining water does not tend to run out, due to capillary action, or surface tension, and because of the difficulty of the entrance of air for displacement, the faucet is dripless, and may safely be installed without the need of a drip or waste receptacle beneath it.

Aside from this, the dripless feature of the construction here disclosed may be further explained as follows:

The three passageways 22 have a combined cross sectional area slightly less than that of the opening through spout 19 and spout chamber 6. Together, these openings, downstream of the valve, from outlet passageways having a constricted area less than that of the inlet 9, bore 8, and valve chamber 5, on the upstream side of the valve closure. Water entering from supply tube 39 under a constant head flows through the whole valve system at a constant rate of flow. Since passageways 22 are constricted—that is, have a smaller aggregate cross section than the passageways upstream of the valve—and since spout 19 has an interior passageway only slightly larger, the rate of flow downstream from the valve will be faster than that upstream thereof. The flow will attain its greatest speed through passage-

ways 22. The flow through these passageways, as well as through spout 19, builds up kinetic energy according to the well known formula

$$K = \frac{MV^2}{2}$$

where K =kinetic energy, M =mass and V =velocity. The result is that, despite surface friction and retarding due to change of direction, the velocity of flow is greater downstream of the valve than upstream of the valve and is greater than would be the case if the downstream passageways were the same size as the upstream passageways, or, were not constricted. The constriction of passageways 22 (as well as spout 19) therefore, is responsible for the translation of kinetic energy from the potential energy of the head pressure, and for the increase of velocity in the downstream flow. Under these conditions, when the valve is quickly closed the kinetic energy in the downstream flow carries the column of water in passageways 22 and in spout 19 outward until it is dissipated by friction and the pressure of the atmosphere. This accounts for the formation of a partial vacuum in the upper ends of passageways 22 for an instant after the valve is quickly closed. The kinetic energy and momentum of flow carry a portion of the water column out of the end of the spout. The next instant, after this energy has been expended, atmospheric pressure forces the column of water remaining in these passageways back from the end of spout 19 and up into them until the vacuum disappears.

Theoretically, disregarding friction, the smaller the downstream passageways, the greater the above described effect. Practically, constriction is limited as the point is reached where friction offsets the gain in kinetic energy due to increased velocity, for the purposes here desired.

Another result of the constriction of passageways 22 is that, since the velocity of flow through them is greater than it would be if they were not constricted, the water column travels further through them (along their length) during the first instant, above mentioned, after the valve is closed. Thus a greater length of water column is run out of the end of spout 19, and therefore there is a greater length of pull back into the spout the next instant, than there would be, if there was no constriction on the downstream side of the valve.

While I have described the preferred forms of my device, it is obvious that many modifications can be made, but that the resultant device would still remain within the spirit and intentions of my invention, and therefore, wish to be limited only by the following claims.

I claim:

1. In a water faucet having a cylindrical body, an attaching flange joined to the side thereof, an inlet entering through said flange, a valve chamber formed at one end of said valve body having a valve seat and an inlet chamber connecting to said inlet, and a spout chamber at the opposite end of said valve body, the combination therewith of means to control dripping including a threaded valve stem and a valve plug thereon adapted to close on said valve seat, a closing spring on said valve stem adapted to aid closing motion of said stem to provide quick closing of said plug on said seat, a spout having an inside diameter sufficiently constricted to retain water therein by surface tension connected to said spout chamber; a plurality of

passageways having an aggregate cross sectional area constricted relative to said spout connecting said valve chamber with said spout chamber whereby water flowing therethrough attains sufficient velocity and kinetic energy to continue to flow momentarily out of said spout after said valve is quickly closed and water remaining in said spout will be forced inward from the outer end portion thereof by atmospheric pressure.

2. In a water faucet having a cylindrical body, a mounting flange formed on one side thereof, a valve chamber at one end thereof having a valve seat at its bottom, an inlet opening below said valve seat, and a spout chamber formed within the opposite end of said body, the combination therewith of means for controlling dripping including a valve plug operative on said valve seat, means for causing a quick closing of said valve plug, a passageway extending longitudinally through said body connecting said valve chamber with said spout chamber, having a cross sectional area constricted relative to said inlet opening and valve chamber, and a spout connected to said spout chamber having an internal opening sufficiently small to retain water therein by surface tension, said passageway being restricted relative to said spout.

3. In a water faucet having a cylindrical body, a mounting flange formed on one side thereof, a valve chamber at one end thereof having a valve seat at its bottom, an inlet opening below said valve seat, and a spout chamber formed within the opposite end of said body, the combination therewith of means for controlling dripping including a valve plug operative on said valve seat, means for causing a quick closing of said valve plug, a passageway extending longitudinally through said body connecting said valve chamber with said spout chamber, having a cross sectional area constricted relative to said inlet opening and valve chamber, and a spout con-

nected to said spout chamber having an internal opening sufficiently small to retain water therein by surface tension but larger than the cross-sectional area of said passageway; the constriction of said passageway being sufficient so that the velocity of flow downstream of said valve is increased to provide kinetic energy sufficient to force a portion of the water flowing through said passageway and spout out of the end of said spout after said valve plug is closed quickly on said seat, whereby a vacuum is momentarily formed in said passageway and immediately thereafter the water remaining in the outer portion of said spout is forced back into said spout and passageway to fill the space in which said vacuum was formed.
